UNITED STATES PATENT OFFICE.

JOHN GOOD, OF GARDEN CITY, NEW YORK, ASSIGNOR TO GOOD INVENTIONS CO., OF NEW YORK, N. Y., A CORPORATION OF NEW YORK.

ENGINE COOLING SYSTEM.

Application filed October 3, 1924. Serial No. 741,502.

The invention relates to engine cooling systems and consists in the organization of parts according to the principles exemplified in the accompanying drawing and below described, whereby the temperature of the engine cylinders or water jackets is controlled by variation in pressure of the water or such other liquid as may be used as the heat abstracting medium.

10 In said drawing, Figure 1 is a side elevation, partly in section of a conventional automobile engine and its cooling system; and

Figure 2, a large scale detail section of the venting and pressure controlling means.

15 The construction and mode of operation of the engine will be recognized without description; its cooling system comprises the usual water jacket 1 surrounding the engine cylinders, the usual radiator 2, and the usual 20 top and bottom water connections 3 and 4.

In the engine shown, the cooling system operates according to the so-called thermosiphon principle, but a water pump could be applied to the system if desired. In either 25 case the water heated by the combustion in the engine cylinders circulates through the upper radiator connection 3 into, and downwardly through the radiator, where it is cooled by the air flowing through the latter 30 and thence through the bottom connection 4 back to the jacket.

The connected passages in which the cooling liquid is contained constitute a containing space which, according to this invention, 35 is vented to atmosphere when the engine is at less than its normal or some desired operating temperature, or when it is not working, but which becomes a closed or a confined space, as by the closing of the vent, 40 after the engine has been started and warmed up and is working. The vent is located in the upper part of the system, preferably in the removable cap 5, through which the radiator is filled, though it might be placed 45 elsewhere, and in the present case it is constituted by the passage 6 in a regulating set screw 7 carried by the cap. The vent passage is controlled, in the present case, by a thermally operated valve 8, the thermal element 9 of which is mounted in a cylindrical 50 perforated frame or casing 10 screwed to the bottom of the radiator cap in a position where it may experience the temperature of the cooling water, or of the water vapor 55 above the level thereof as the case may be.

When the engine is started and the temperature of the jacket water, or cooling liquid, rises to some predetermined temperature, considered appropriate for the best operation of the engine, say about 212° F. the 60 thermal valve 8 closes the vent and thereafter pressure is developed within the closed space of the cooling system as the result of the further expansion of the liquid. The adjusting screw 7, in the present case, controls the temperature at which the vent is closed and for this purpose it is provided with a finger 11 which, in connection with appropriate markings on the top of the radiator cap, serves as an index. Screwing 65 the regulating screw downward causes the vent to be closed at a lower temperature and vice versa. The thermally controlled vent just described constitutes one of several different forms of mechanism by which the 70 purposes of this invention may be accomplished; it is preferred because of its simplicity, being, in fact, not substantially different from the automatic air valves used on steam and other radiators in house heating systems.

After the desired temperature has been reached and the vent has been closed, the pressure developed by further increase of the temperature in the cooling liquid becomes effective upon a diaphragm or other motor means connected into the system, which by its operation controls some suitable means for controlling the temperature of the cooling liquid. In the present case 90 the pressure variation is made effective through the passage 12, upon a diaphragm 13 which is thereby displaced against the pressure of an adjustable spring 14 to open a set of pivoted shutters 15 mounted in front 95 of the radiator and controlling the fan-produced air flow therethrough. By the cooling effect thus produced on the liquid in the radiator, the total volume of cooling liquid in the system tends to diminish, with the 100 result that automatically, a substantially constant pressure condition is obtained corresponding to the desired jacket temperature and a substantially constant engine temperature is thereby secured, regardless of 105 atmospheric temperature.

The operation of the shutter mechanism, or such other air flow or temperature control as may be employed, is very positively effected by the diaphragm motor which pos- 110

seses abundant power for operating purposes and is far more reliable than the thermostatic elements heretofore used for shutter control.

- 5 While the vent 6 is open, it permits escape of air or water vapor or, if the radiator has been completely filled, of excess cooling liquid. And if, after the closing of the vent, there is at any time an excess volume of 10 liquid or vapor above that necessary for producing the requisite diaphragm operating pressure, it is vented through the spring seated safety valve 16, provided in the cap, but ordinarily this safety valve is not called 15 into operation since the effect of the opening of the radiator shutters 15 is to produce an almost immediate reduction of the temperature, and hence of the pressure of the cooling liquid.
- 20 By means of apparatus as above described it is possible to maintain the engine temperature somewhat higher than can ordinarily be obtained in liquid cooling systems operating at atmospheric pressure, because 25 the adjusting screw 7 may, for example, be set to close, at say 212° F. so that as soon as the water reaches that point, the shutters open immediately, and as soon as it drops, one or two degrees, they again close, thus 30 maintaining the water close to the boiling point, though boiling is not intended and does not occur with proper setting of the shutter control. Moreover, in wintertime, when alcohol or similar additions are made 35 to the water system to guard against freezing, the regulating screw may be set so that the vent is closed much earlier, that is to say, at a lower temperature, thereby avoiding loss of the alcohol as vapor through the 40 vent, and I have found, contrary to expectation that such low temperature adjustment, for saving alcohol, does not result in any appreciable reduction of the temperature in the cylinder block. In other words, the cylinders will run at the same temperature with water in the system at 212° F. as they will 45 with an alcohol water mixture at a much lower temperature, say 140° F., and from this it will be seen that while the system described 50 possesses the particular advantage of conserving alcohol, it also enables the cylinder temperature to be maintained at substantially the same temperature with alcohol mixture as with pure water, an effect 55 which cannot readily be obtained in atmospheric cooling systems because of the boiling away of the alcohol at a lower temperature. It is one of the features of my present invention that the cooling effect is accomplished by a liquid or liquid mixture of 60 greater volatility than water, maintained under pressure greater than atmosphere. The power available at the diaphragm is adequate for operating other engine controls 65 besides the shutters, such for example

as the choker or mixture control or any other device which may require adjustment or resetting when the engine has warmed up.

It will be understood that the particular construction described is merely exemplary 70 of the principles involved in the invention and that, except in so far as specified in the invention and that, except in so far as specified in the claims, there is no limitation to the arrangement, type or design of the apparatus 75 illustrated.

Claims:

1. The combination in an internal combustion engine of an initially open liquid-containing cooling system therefor, means 80 for closing the system and means operated by the pressure therein for controlling the temperature of the system.

2. The combination in an internal combustion engine, of a liquid cooling system 85 therefor having a vent, a thermostat for closing the vent at a pre-determined temperature and means operated by the pressure thereafter developed in the system for controlling the temperature thereof. 90

3. The combination, in an internal combustion engine, of a liquid cooling system therefor which is initially open but normally closed, as when the engine is warmed up, an air flow for cooling the liquid, and means 95 operated by the pressure developed in the system for controlling the air flow.

4. The combination, in an internal combustion engine, of means for cooling the same, comprising shutter means, a body of 100 liquid contained in a vented space subject to the engine cylinder temperature, an automatic closure for the vent and means whereby the pressure developed in said body of liquid operates said shutters. 105

5. The combination in an internal combustion engine, of a cooling system therefor, containing a liquid of greater volatility than water and having a vent, means for closing the vent when the engine is warmed up and 110 means operated by the pressure in the system for controlling the temperature of the liquid.

6. In an internal combustion engine cooling system, the combination of a radiator having a vent, thermostatic means for closing the vent and thereby preventing the escape of cooling liquid as vapor and means operative only when the vent is closed to prevent excessive temperatures in the cooling system. 115

7. The combination with an internal combustion engine having a control adapted to occupy one position or another according as the engine is cold or warmed up, of a liquid cooling system for the engine having a vent, a thermally operated closure for the vent and means operated by the pressure thereafter developed in the system for actuating said control. 125

8. In an engine cooling system employing 130

a cooling medium of greater volatility than water, the method of controlling the same which consists in subjecting the medium to a pressure greater than atmospheric and cooling the same before the medium reaches the normal operating temperature of the engine.

9. In a normally open engine cooling system employing a cooling medium of greater

volatility than water, the method of controlling the same which consists in closing the system before the medium reaches a temperature at which substantial vaporization occurs and thereupon subjecting the medium to a cooling air flow. 10

In testimony whereof, I have signed this specification.

JOHN GOOD.
